UNITED STATES PATENT OFFICE.

ROY D. CONWAY, OF CHATHAM, NEW JERSEY, ASSIGNOR TO WESTERN ELECTRIC COMPANY, INCORPORATED, OF NEW YORK, N. Y., A CORPORATION OF NEW YORK.

ELECTRIC REGULATOR.

Application filed July 24, 1919. Serial No. 313,033.

To all whom it may concern:

Be it known that I, ROY D. CONWAY, a citizen of the United States, residing at Chatham, in the county of Morris, State of New Jersey, have invented certain new and useful Improvements in Electric Regulators, of which the following is a full, clear, concise, and exact description.

This invention relates to arrangements for regulating an electrical characteristic of a circuit such as the intensity of current flowing therethrough.

One of the objects of this invention is to provide means for insuring a flow of current of constant intensity over a circuit. Another object consists in providing means for automatically increasing the resistance in a circuit whenever the current flow therethrough has a tendency to increase, and means for automatically reducing the resistance as the current flow decreases. A further object consists in the provision of means for cutting in or out resistance in any circuit by successive steps in order to hold constant an electrical characteristic in a portion of the circuit. Other objects of this invention will appear in the detailed description to be given later.

It is often found desirable to associate with a work circuit including translating devices such, for example, as a circuit including the filament of a vacuum tube repeater, an arrangement for regulating the current flow therethrough. This is because the voltage at the source supplying the current in the circuit may have a tendency to vary beyond the limits within which satisfactory operation of the apparatus will result. As it has been found that a vacuum tube repeater will give better service if the current flow through its filament circuit remains constant, the regulating apparatus comprising this invention has been provided.

The regulating apparatus of this invention includes a voltmeter relay sensitive to slight variations in voltage and whose winding is connected to the source which supplies current for the work circuit. An increase in the voltage of this source will cause a circuit to be closed over the needle and one of the contacts of the voltmeter thereby operating a resistance varying mechanism to add a certain amount of resistance in series

with the winding of the voltmeter relay, and also in series with the filament contained in the work circuit. If the resistance thus added to the voltmeter circuit and the work circuit is not sufficient to counter-balance the increase in current due to the change in voltage, the voltmeter needle will not fall back to neutral position but will still serve to hold closed the circuit over the contact of the voltmeter. Accordingly the resistance varying mechanism will continue to operate and will add further resistance units to the circuit including the voltmeter winding and the work circuit until the increase in current flow has been counter-balanced and the needle returned to neutral position.

If the current flow from the source decreases, a circuit is closed over the needle and the other contact of the voltmeter which operates the resistance varying mechanism to reduce the resistance in the voltmeter circuit and the work circuit in proportion to the decrease in voltage.

The resistance varying mechanism comprises a series of relays under the control of the contacts of the voltmeter. The relays of this series are adapted to control the association with the voltmeter circuit and the work circuit of a plurality of resistance units. Means are also provided for insuring the successive action of this series of relays so that only one resistance may be cut in or out of the work circuit and the voltmeter circuit at one time. In the preferred form of this invention this is accomplished by employing an interrupter which controls the energizing circuit for this series of relays to open said energizing circuit as soon as one of the resistance controlling relays has been energized or deenergized and closes said circuit after the addition or subtraction of the resistance in the work circuit has changed the current in the voltmeter circuit to bring the voltmeter needle back to neutral position. However, if the resistance added is not sufficient to bring the needle back to neutral position an additional resistance controlling relay will be operated as soon as the interrupter has closed the energizing circuit again.

This invention may now be more fully understood from the following detailed description taken in connection with the ac-

companying drawing, in which Fig. 1 represents the preferred form of the circuit arrangement of this invention and Fig. 2 is a modification thereof.

5 Referring to Fig. 1, connected to a battery 3 is a circuit containing a plurality of normally short-circuited resistance units 4, 5, 6 and 7, and the winding of a voltmeter relay 8. These resistance units and the battery are 10 also included in a circuit which supplies the heating current for a plurality of filaments 9 to 14, inclusive, which may be connected in parallel by groups. The voltmeter relay 8 has a needle 9 located between two stationary contacts 10 and 11. Since these contacts are extremely delicate, the needle 9 is connected to an intermediate point of a circuit containing the high resistances 17, 18 and battery 3, so that only a fraction of the total 15 potential of battery 3 may be applied to the voltmeter needle in case the total potential of battery 3 would be injurious to the contacts if applied directly.

Under the control of the voltmeter needle 9 and contact 10 is a relay 20 which, through the intermediary of the movable contacts of a relay 21, serves to control the energization of the series of relays 22 to 25 inclusive. The energization of this series of relays 22-25 inclusive, serves to open the short circuits around resistances 4 to 7 inclusive, thereby adding these resistances 4 to 7 inclusive to the circuit including the winding of voltmeter relay 8 and the filaments 30 9-14 inclusive of the vacuum tube repeaters. The resistances 4-7 inclusive have a value predetermined with respect to the adjustment of the contacts of the voltmeter relay 8. An interrupter 28, by periodically 35 opening and closing the energizing circuit of relay 21, insures that the relays 22 to 25 inclusive will be operated successively and that there will be no surging of current therein. Under the control of needle 9 and 40 contact 11, is a relay 39 which, through the intermediary of the movable contact of a relay 31, serves to control the deenergization of relays 22 to 25 inclusive to subtract the resistance elements 4-7 inclusive from 45 the voltmeter and the work circuit. The successive deenergization of the relays 22-25 inclusive is secured by the operation of the interrupter 28.

In case the current supplied to the work 50 circuit is large, it may be necessary to connect an additional relay 33 in the energizing circuit of relay 22 and to employ the movable contacts of this relay 33 as additional shunt paths for resistance 4 so as to make 55 the current flowing through any one movable contact small enough that the contact will not be injured when the circuit is open or closed. For a similar purpose, relays 34, 35 and 36 may be connected to the energizing 60 circuits of relays 23, 24 and 25, respectively.

The operation of the arrangement of this invention is as follows:

The circuit normally closed through the winding of the voltmeter relay 8 is from ground, battery 3, movable contacts of relay 33 and movable contact 37 of relay 22 in parallel, conductor 38, movable contacts of relay 34 and movable contacts 39 of relay 23 in parallel, conductor 40, movable contacts of relay 35 and movable contact 41 of relay 24 in parallel, conductor 42, movable contacts of relay 36 and movable contact 43 of relay 25 in parallel, conductor 44, winding of voltmeter relay 8, to ground. The heating circuit for the filaments 9 to 14 inclusive 70 may be traced from ground, battery 3, the shunt paths for resistances 4 to 7, inclusive, traced above, conductor 44, through the filaments to ground.

An increase in the voltage of source 3 will 85 be indicated by a deflection to the right of the needle of the voltmeter 8 thereby closing the following circuit from ground, battery 3, resistance 18, needle 9, contact 10, winding of relay 20, to ground. The closing of 90 the above described circuit energizes relay 20 which pulls up its movable contacts 46, 47, and closes the following circuit from ground, movable contact 46, winding of relay 21, movable contact 48 and winding of inter- 95 ruptor 28, to battery and ground. The energization of relay 21 will cause its movable contact to be pulled over and close the following circuit from ground, movable contact 47 of relay 20, movable contact 49 of 100 relay 21, conductor 50, winding of relay 22 to battery and ground and also winding of relay 33 to battery and ground. This energizes relays 22 and 33 which pull up their 105 movable contacts, thereby opening the shunt paths around resistance 4. The common branch in the filament circuit and the voltmeter circuit may then be traced as follows—ground, battery 3, resistance 4, shunt paths for resistances 5, 6 and 7 and conductor 110 44. The closing of the movable contact 51 of relay 22 locks relays 22 and 33 over the following circuit; from ground, battery 3, relay 33 and from ground, battery 3, relay 22 through movable contact 51, conductor 53, conductor 54, movable contact 55 of relay 115 30, to ground. Thus it is seen that the operation of relays 22 and 33 have added resistance 4 to the work circuit to counter-balance the increase in the voltage of source 3, thereby tending to prevent an increase in the 120 heating current for the work circuit.

If the addition of resistance 4 to the work circuit and the voltmeter circuit is sufficient to counterbalance the increase in the voltage 125 of source 3, the voltmeter needle 9 will return to neutral position and open the circuit formerly closed through the winding of relay 20, thereby deenergizing relay 20 which allows its movable contacts to fall back. The 130

operation of the interrupter or self-interrupted relay 28 should be so timed that when, as just assumed, the addition of one resistance is sufficient to counter-balance an increase in voltage of the source 3, relays 20, 21, 22 and 33 will have operated and the voltmeter needle 9 will have fallen back to neutral position before the self-interrupted relay 28 will have had time to attract its movable contact 48 and break the energizing circuit for relay 22, previously traced. With the self-interrupted relay 28 timed in such a manner, the voltmeter needle, as described above, will fall back to neutral position thereby deenergizing relay 20. The deenergization of relay 20 will then break the circuit containing the winding of relay 21, the movable contact and the winding of the self-interrupted relay 28, before this self-interrupted relay has had time to attract its movable contact to open the circuit. In the preferred arrangement this self-interrupted relay should be adjusted to open the circuit from four to sixteen times a second.

If the addition of resistance 4 is not sufficient to counter-balance the increase in the voltage of battery 3, the needle of the voltmeter relay will not return to neutral position, but will remain deflected to the right and the relay 20 will remain energized and keep its movable contacts pulled over. As soon as sufficient time has elapsed after the energization of relay 20, the self-interrupted relay 28 will attract its movable contact 48 thereby opening the following circuit; ground, movable contact 46 of relay 20, winding of relay 21, movable contact 48, winding of relay 28 to battery and ground. The opening of this circuit will deenergize relay 21 which will allow its movable contact 49 to fall back and close the following circuit; ground, movable contact 47 of relay 20, movable contact 49, conductor 56, movable contact 57, conductor 58, winding of relay 23, to battery and ground, and conductor 59, winding of relay 34, to battery and ground. This will energize relays 23 and 34 to close their movable contacts and lock relays 23 and 34 over the following circuit; from ground, battery, winding of relay 34, conductor 59, and ground, battery, winding of relay 23, through movable contact 61, conductor 62, conductor 64, movable contact 66 of relay 31 to ground. The attraction of the movable contacts of relay 34 and movable contact 39 of relay 23 will open the shunt paths around resistance 5 thereby inserting this resistance in the work circuit and the voltmeter relay circuit. The operation of relay 23 also breaks the locking circuit for relays 22 and 33, previously traced, and removes them from under the control of relay 30 by locking them over the following circuit; ground, battery, winding of relay 33, and ground, battery, winding of

relay 22, movable contact 51, conductor 53, movable contact 70, to ground. Thus it is seen that with the operation of relay 23, both resistances 4 and 5 are included in the voltmeter circuit and the work circuit.

If the addition of resistance 5 to the voltmeter circuit is sufficient to counter-balance the increase in the voltage of battery 3, the voltmeter needle 9 will fall back to neutral position thereby deenergizing relay 20 before sufficient time has elapsed for the previously deenergized self-interrupted relay to allow its movable contact to fall back and complete the circuit through the winding of relay 21.

If the addition of resistance 5 is not sufficient to counter-balance the increase in the voltage the voltmeter needle will not return to neutral position, but will remain deflected to the right, thereby keeping closed the movable contacts of relay 20. As soon as sufficient time has elapsed, the movable contact 48 of the self-interrupted relay 28 will fall back and complete the energizing circuit previously traced for the winding of relay 21.

This will energize relay 21 which will pull over its movable contact 49 and close the following circuit; ground, movable contact 47, movable contact 49, conductors 50 and 72, movable contact 73, winding of relay 24, to battery and ground, and winding of relay 35, to battery and ground. Relays 24 and 35 will then attract their movable contacts and become locked up over the following circuit; ground, battery, winding of relay 35, and ground, battery, winding of relay 24, movable contact 74, conductor 75, conductor 54, movable contact 55 of relay 30, to ground. The attraction of the

movable contacts of relay 35 and the movable contact 41 of relay 24 will open the shunt paths for resistance 6 thereby inserting the resistance 6 in the voltmeter circuit and the work circuit. The operation of relay 24 also breaks the locking circuit for

relays 23 and 34, traced above, and removes these two relays from under the control of the movable contact of relay 30 by locking them over the following circuit; ground, battery, winding of relay 34, and ground, battery, winding of relay 23, movable contact 61, conductor 62, movable contact 80, to ground. Thus it is seen that with the operation of relays 24 and 35, resistances 4, 5 and 6 are included in the voltmeter circuit and the work circuit.

If the addition of resistance 6 is sufficient to counter-balance the increase in voltage of source 3, the voltmeter needle 9 will return to neutral position, deenergizing relay 20 before sufficient time has elapsed for the self-interrupted relay to attract its movable contact and break the energizing circuit for relay 21.

However, if the addition of resistance 6 is

sufficient to counter-balance the increase in voltage of source 3, the voltmeter needle 9 will return to neutral position, deenergizing relay 20 before sufficient time has elapsed for the self-interrupted relay to attract its movable contact and break the energizing circuit for relay 21.

However, if the addition of resistance 6 is

sufficient to counter-balance the increase in voltage of source 3, the voltmeter needle 9 will return to neutral position, deenergizing relay 20 before sufficient time has elapsed for the self-interrupted relay to attract its movable contact and break the energizing circuit for relay 21.

However, if the addition of resistance 6 is

sufficient to counter-balance the increase in voltage of source 3, the voltmeter needle 9 will return to neutral position, deenergizing relay 20 before sufficient time has elapsed for the self-interrupted relay to attract its movable contact and break the energizing circuit for relay 21.

not sufficient to counter-balance the increase in voltage of source 3, the voltmeter needle will remain deflected to the right, thereby keeping the contacts of relay 20 pulled over. 5 As soon as sufficient time has elapsed, the self-interrupted relay 28 will attract its movable contact 48, thereby breaking the energizing circuit for relay 21. The de-energization of relay 21 will allow its movable contact to fall back and close the following circuit; ground, movable contact 47 of relay 20, movable contact 49, conductor 83, movable contact 84, winding of relay 25, to battery and ground, and winding of relay 10 36, to battery and ground. The closing of this circuit will energize relays 25 and 36 so that they will pull up their movable contacts and become locked up over the following circuit; ground, battery, winding of relay 36, 15 and ground, battery, winding of relay 25, movable contact 87, conductor 64, movable contact 66 of relay 31, to ground. The attraction of the movable contacts of relay 36 and the movable contact 43 of relay 25 will 20 open the shunt paths around resistance 7 thereby inserting this resistance in the work circuit and the voltmeter circuit. The operation of relay 25 also breaks the locking circuit of relays 24 and 35, traced above, and 25 removes these two relays from under the control of the movable contact 55 of relay 30 by locking them up over the following circuit; ground, battery, winding of relay 35, and ground, battery, winding of relay 24, 30 movable contact 74, conductor 75, movable contact 89 to ground.

If the addition of resistance 7 to the voltmeter circuit and the work circuit is sufficient to counter-balance the increase in voltage of source 3, the voltmeter needle will return to neutral position thereby deenergizing relay 20 before sufficient time has elapsed for the interrupted relay 28 to operate.

While the series of relays which control the amount of resistance in the voltmeter circuit and the work circuit is shown consisting of only four relays 22 to 25, inclusive, and their associated resistance elements, it will be understood that this series is not limited 45 to any specific number, but that any desirable number of such relays and resistance elements may be included in the circuit arrangement of the regulator. By this means any rise in voltage which may be encountered can 50 be compensated for so as to limit the current flow and the current flow can be held within any desirable limits by a suitable number of relays controlling resistance elements.

The operation of this invention for a decrease in voltage may be explained as follows: If for example, after the rise in voltage at the source 3 has been counter-balanced by the operation of relays 22 to 25, inclusive, and the subsequent addition to the work circuit and the voltmeter circuit of resistances 4

to 7 inclusive, the voltage should start to fall, the needle of the voltmeter will be deflected to the left and close the following circuit; from ground, battery 3, resistance 18, needle 9, contact 11, winding of relay 30 to ground. 70 The closing of this circuit will energize relay 30 which will pull over its movable contact 55 and close the following circuit; ground, movable contact 55, winding of relay 31, movable contact 48, winding of self-interrupted relay 28, to battery and ground, thereby energizing relays 28 and 31. The breaking of the circuit containing the movable contact 55 of relay 30, and conductor 54, by the pulling up of movable contact 55 will 80 not disturb in any way the energizing circuits for relays 22 to 25, inclusive, since the operation of relay 25, previously described, removed relay 24 from the control of this movable contact. Relay 31 will pull over its 85 movable contact 66 thereby opening the following circuit; ground and movable contact 66, conductor 64, movable contact 87 of relay 25, winding of relay 25, to battery and ground and the winding of relay 36 to battery and ground. The breaking of this circuit will deenergize relays 25 and 36 which will allow their movable contacts to fall back and close the shunt paths for resistance 7, thereby decreasing the resistance in the work 90 circuit. With the deenergization of relay 25, the locking circuit for relays 24 and 35 which were previously locked through movable contact 89 of relay 25 to ground, will be changed to the following circuit under the 100 control of the movable contact 66 of relay 31; from ground, battery, winding of relay 35, and ground, battery, winding of relay 24, movable contact 74 of relay 24, conductor 75, conductor 54, movable contact 66 of energized relay 31, to ground. At the same time relays 25 and 36 will be put under the control of relay 20 by the connection of their windings through movable contact 84 of relay 24 to conductor 83. 110

If the subtraction of resistance 7 from the voltmeter circuit is sufficient to compensate for the decrease in voltage of source 3, the needle of the voltmeter will return to neutral position to deenergize relays 30 and 31 before the self-interrupted relay 28 has had sufficient time to operate. With the deenergization of relays 30 and 31, the locking circuit for relays 24 and 35 is placed under the control of relay 30 on account of the falling back of movable contacts 55 and 66, and is traced as follows: from ground, movable contact 55, conductor 54, conductor 75, movable contact 74, winding of relay 24 to battery and ground, and winding of relay 35 to 115 battery and ground. 120

However, if the subtraction of resistance 7 is not sufficient to counter-balance the decrease in voltage of source 3, the needle of the voltmeter will remain deflected to the 130

left and keep energized relays 30 and 31. The locking circuit for relays 24 and 35 therefore will remain under the control of movable contact 66 of energized relay 31 instead of having the locking circuit changed so as to terminate in the movable contact 55 of relay 30 described above in the case where the addition of relay 7 was sufficient to bring the voltmeter needle back to neutral position. As soon as sufficient time has elapsed the self-interrupted relay 28 will attract its movable contact and open the following circuit; ground, battery, winding of relay 28, movable contact 48, winding of relay 31, movable contact 55 of energized relay 30, to ground. The opening of this circuit will de-energize relay 31 thereby allowing movable contact 66 to fall back. The falling back of movable contact 66 will break the following circuit; ground, battery, winding of relay 35, and ground, battery, winding of relay 24, movable contact 74, conductors 75 and 54, movable contact 66, to ground. The opening of this circuit will deenergize relays 24 and 35, thereby allowing their movable contacts to fall back and close the shunt paths for resistance 6. The deenergization of relay 24 places relay 24 under the control of relay 20 by the following connection to the main conductor 72 so that in case the voltage should subsequently rise in value, relay 20 will operate to reenergize relays 24 and 35; from ground, battery, winding of relay 24, movable contact 73 of relay 23 to conductor 72. Before relay 24 was deenergized, relays 23 and 34 were locked up over the movable contact 80 of relay 24. But after the deenergization of relay 24 their locking circuit is changed to the following circuit; ground, battery, winding of relay 23, and ground, battery, winding of relay 34, movable contact 61 of relay 23, conductors 62 and 64, movable contact 66, to ground.

If the subtraction of resistance 6 is sufficient to counterbalance the decrease in voltage, the voltmeter needle is returned to neutral position and relay 30 deenergized before sufficient time has elapsed for the movable contact of relay 28 to fall back and reenergize relay 31.

However, if the subtraction of resistance 6 is not sufficient to counterbalance the decrease in voltage, the voltmeter needle will remain deflected to the left, thereby keeping relay 30 energized. As soon as sufficient time has elapsed for the movable contact 48 to fall back to close the energizing circuit for relay 31, relay 31 will attract its armature 66 and break the locking circuit previously described for relays 23 and 34. The deenergization of these relays will close the shunt paths for resistance 5, will connect their windings to the conductor 56 so as to place themselves under the control of relay 20 for a subsequent increase in voltage, and will

also transfer the locking circuit for relay 22 to the control of relay 30.

If the subtraction of resistance 5 is not sufficient to counterbalance the change in voltage, relay 31 will be deenergized by the 70 operation of self-interrupted relay 28 and break the locking circuit of relays 22 and 33 thereby short-circuiting resistance 4.

Thus, it is seen that at any given time in the operation of this invention only one relay of a series 22 to 25, inclusive, is under the control of the left contact of the voltmeter relay and only one of the series is under the control of the right contact of the voltmeter relay. If, for example, a certain change in 80 voltage has occurred to operate relays 22 and 23 while relays 24 and 25 are still de-energized, relay 23 would be under the control of contact 11 of the voltmeter while relay 24 would be under the control of the contact 10 of the voltmeter, thus providing means for counterbalancing a further increase in voltage or a decrease in voltage.

Fig. 2 illustrates a modification that may be made in Fig. 1 by the substitution for the self-interrupted relay 28, of a motor-driven interrupter 95 which may be operated continuously to make and break the circuit connections between ground, battery 3, contact 96 of the interrupter and the windings of 95 relays 21 and 31. The operation of the circuit arrangement with the motor-driven interrupter is similar to that described above with the self-interrupted relay, the only difference being that the self-interrupted relay 100 operates to make and break the circuit connections to the windings of relays 21 and 31 only when relay 20 or relay 30 is energized while the motor-driven interrupter will operate to make and break the circuit independent of the energization of relays 20 and 30.

While this invention has been disclosed in particular forms which have been found desirable, it will be understood that it may be 110 embodied in many and widely different forms without departing from the spirit of this invention, as defined in the appended claims.

What is claimed is:

1. The combination of a solenoid, a plurality of resistance elements for connection in or out of circuit with said solenoid, relays individual to said resistance elements for controlling said elements, and means 120 comprising an interrupter for placing said relays under the control of said solenoid.

2. The combination of a solenoid, a work circuit, a plurality of resistances in said work circuit controlled by said solenoid, 125 movable contacts individual to said resistances, and means comprising an interrupter for causing said movable contacts to be controlled by said solenoid.

3. A regulator comprising a solenoid, a 130

- source of voltage, a plurality of impedance elements, a circuit containing said solenoid, said source of voltage and said impedance elements, shunt paths for said elements, and means comprising an interrupter and a relay responsive to said solenoid for controlling said shunt paths.
4. A regulator comprising an electroresponsive device, a source of voltage, a plurality of impedance elements, a circuit containing said device, said source of voltage, and said impedance elements, shunt paths for said elements, means comprising an interrupter and a relay responsive to said device for controlling said shunt paths for an increase in voltage of said source, and means comprising said interrupter and a second relay responsive to said device for controlling said shunt paths for a decrease in the voltage of said source.
5. A regulator comprising an electroresponsive device, a source of voltage, a plurality of regulating elements, a circuit containing said device, said source of voltage and said regulating elements, one of said regulating elements being normally under the control of said device, means comprising an interrupter for placing another of said elements under the control of said device.
6. A regulator comprising a voltmeter, a source of voltage, a plurality of resistance elements, a circuit containing said voltmeter, said source of voltage and said resistance elements, one of said resistance elements being normally under the control of said voltmeter, and means comprising a continuously operating interrupter for placing another of said elements under the control of said voltmeter.
7. In a system of distribution, a source of voltage, a voltmeter, a plurality of impedance elements, a circuit containing said voltmeter, said source of voltage and said impedance elements, shunt paths for said impedance elements, means responsive to an increase in voltage for controlling the opening of one of said shunt paths, and means responsive to a decrease in voltage for controlling the closing of one of said shunt paths, each of said means comprising an interrupter.
8. In a system of distribution, a source of voltage, a plurality of resistance elements, a work circuit containing said source of voltage and said resistance elements, and means for holding substantially constant the current in said work circuit, said means comprising a voltmeter associated with said work circuit and means comprising an interrupter, and a plurality of relays responsive to said voltmeter for effectively disconnecting said resistances from said work circuit, and a plurality of relays for subsequently connecting said resistances in said work circuit.
9. In a system of distribution, a source of voltage, a plurality of resistance elements, a work circuit containing said source and said resistance elements and means for controlling the current in said work circuit, said means comprising a voltmeter associated with said work circuit, shunt paths for said resistance elements, an interrupter, a relay responsive to said voltmeter, a set of relays comprising a relay individual to each of said shunt paths, said set being responsive to said first relay only when said interrupter is operated.
10. A regulator comprising a voltmeter, a plurality of regulating elements, a solenoid, an energizing circuit for said solenoid, means responsive to said voltmeter for closing said energizing circuit, one of said regulating elements being normally under the control of said solenoid, means for periodically opening and closing said energizing circuit after said voltmeter has operated to close said circuit, said means operating to transfer the control of said solenoid to another of said regulating elements.
11. In a system of distribution, a source of voltage, a work circuit comprising said source, means for holding substantially constant the current in said circuit, said means comprising a voltmeter responsive to a condition of said circuit, a plurality of resistance elements in said circuit, a solenoid, an energizing circuit for said solenoid, means responsive to said voltmeter for closing said energizing circuit, one of said resistances being normally under the control of said solenoid, means for periodically opening and closing said energizing circuit after said voltmeter has operated to close said circuit, said means operating to transfer the control of said solenoid to another of said resistances.
12. A regulator comprising a voltmeter, a plurality of resistance elements, shunt paths individual to said resistances normally closed, a solenoid, an energizing circuit for said solenoid, said solenoid normally controlling the shunt path for one of said resistances, means responsive to said voltmeter for closing said energizing circuit, and means for periodically opening and closing said energizing circuit whereby said solenoid opens one of said shunt paths when said energizing circuit is closed, opens a second of said shunt paths when said circuit is opened and opens a third of said shunt paths when said circuit is closed again.
13. In a system of distribution, a source of voltage, a voltmeter having a winding, a plurality of resistances, shunt paths for said resistances, a circuit containing said source, said resistances and said winding, a work circuit containing said source and said resistances, an automatic means responsive to changes in voltage of said source for control-

ling said shunt paths to regulate said work circuit while maintaining substantially constant the calibration of said voltmeter.

14. In a system of distribution, a source of voltage, a voltmeter having a winding, a plurality of resistances, a circuit containing said source, said resistances and said winding, a work circuit containing said source and said resistances, means comprising a series of relays responsive to changes in voltage of said source for controlling said resistances to hold substantially constant the current in said work circuit while maintaining constant the calibration of said voltmeter.

15. In a system of distribution, a source of voltage, a voltmeter having a winding, a plurality of resistances, a circuit containing said source, said resistances and said winding, a work circuit containing said source and said resistances, and means comprising a relay responsive to changes in voltage of said source, for controlling one of said resistances to vary the calibration of said voltmeter, and to regulate said work circuit, and means comprising an interrupter for transferring the control of said relay to another of said resistances.

16. The combination of a circuit to be regulated, regulating elements therefor, an electroresponsive device for said circuit, circuit connections for said regulating elements, means comprising a series of relays for controlling said circuit connections, and means comprising a continuously operated interrupter for placing said relays under the con-

trol of said device, said interrupter operating independently of the condition of the circuit to be regulated.

17. In an electric system, a series of several solenoids, a master solenoid, connections dependent upon the energization of said master solenoid for successively controlling alternate solenoids of said series, and connections dependent upon the deenergization of said master solenoid for controlling the other solenoids of said series.

18. In an electric system, a work circuit, a series of several regulating elements in said circuit, a solenoid responsive to a condition of said circuit, connections dependent upon the energization of said solenoid for successively controlling alternate elements of said series, and connections dependent upon the deenergization of said solenoid for controlling the remaining elements of said series.

19. In combination, a translating device, a solenoid, a series of several regulating elements, said device, said solenoid and said elements being so connected in circuit that said elements are in series with said solenoid and device in parallel, connections dependent upon the energization of said solenoid for successively controlling alternate elements of said series, and connections dependent upon the deenergization of said solenoid for controlling the remaining regulating elements.

In witness whereof, I hereunto subscribe my name this 21st day of July A. D., 1919.

ROY D. CONWAY.
